United States Patent Office

Des. 177,887

Patented May 29, 1956

177,887

SUCTION CUP

Daniel Waldman, Brooklyn, N. Y.

Application February 24, 1955, Serial No. 34,647

Term of patent 7 years

(Cl. D4—3)

Fig.1

I claim:

The ornamental design for a suction cup, as shown.
